UPHOLSTERY FABRIC

Alfred T. Wilde, North Bergen, N. J.

Application April 12, 1955, Serial No. 35,488

Term of patent 7 years

(Cl. D92—1)

The figure on the drawing is a plan view of an upholstery fabric showing my new design.

My design comprises an alternate arrangement of smooth and corded blocks, each corded block topped by a tinsel strand, and the whole presenting a corrugated effect, all as shown.

I claim:

The ornamental design for an upholstery fabric, substantially as shown and described.
